(57) **CLAIM**

The ornamental design for a flowmeter, as shown and described.

DESCRIPTION

FIG. 1 is a perspective view of a flowmeter showing our new and ornamental design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is further perspective view of FIG. 1; and,

FIG. 9 is further perspective view of FIG. 1.

The portions of the flowmeter shown in broken lines in the figures attached hereto form no part of the claimed design.
